UNITED STATES PATENT OFFICE.

LEWIS L. BEEKEN, OF PITTSBURGH, PENNSYLVANIA.

HYDRAULIC CLASSIFIER.

1,035,145.

Specification of Letters Patent. Patented Aug. 13, 1912.

Application filed April 5, 1912. Serial No. 688,703.

To all whom it may concern:

Be it known that I, LEWIS L. BEEKEN, a citizen of the United States, and a resident of Pittsburgh, in the county of Allegheny and State of Pennsylvania, have invented certain new and useful Improvements in Hydraulic Classifiers, of which the following is a full and clear specification, the novelty being more particularly pointed out in the annexed claims.

This invention relates to hydraulic classifiers and has for its primary object to provide an improved construction, combination and arrangement of parts in devices of this character whereby a rapid accurate classification can be secured with a minimum expenditure of power.

Toward the attainment of these ends my invention contemplates the provision of improved means for feeding the material to a classifier, embodying a sorting column surrounded by a riser column of relatively large diameter, said columns being in communication with each other by means of a hopper having its upper and lower ends merged with said columns respectively. Classifiers of this form have been rendered very inefficient by reason of deposits which become banked on the sloping wall of the hopper, such accumulations being caused at periodic intervals to slide down into the sorting column, sometimes seriously clogging the discharge orifices and always greatly disturbing the working conditions of the classifier. According to the present invention, these objections are overcome by arranging the apparatus which feeds the material to the classifier so that it will discharge within this trouble generating zone, and in revolving the feed pipes as the feeding progresses. By means of this construction water and the composite material are introduced in a manner which prevents the accumulation of the objectionable deposits while at the same time compensating in large measure the loss in velocity due to the larger diameter of the riser chamber.

Another object of my present invention is to provide improved discharge orifices for the sorting column and improved means for relieving the same when clogged.

Other and further objects will appear in the specification and be pointed out in the appended claims, reference being had to the

accompanying drawings exemplifying my invention, and in which—

Figure 1 is a vertical section through a classifier provided with my improvements. Fig. 2 is a top plan view of the same. Fig. 3 is a section on the line III—III, Fig. 1. Fig. 4 is a section on the line IV—IV, Fig. 1. Fig. 5 is a fragmentary side elevation of the lower end of the sorting column.

Referring more particularly to the drawings and to the embodiment shown therein, the composite material together with the water conveying the same is introduced through an intake 1 into a hopper 2, said intake being suitably disposed to discharge the material against the blades 3 of a rotor head carried by a standard 4 which is rigidly mounted by means of a spider 5 in the upper end of an inlet column 6, which extends downwardly through a riser column 7 to be hereinafter referred to. On the lower end of the rotary inlet column 6 is mounted a hollow cap 7' from which project a plurality of radially disposed pipes 8 which discharge downwardly and rearwardly against the inclined walls of a hopper 9 which connects the riser column 7 with a sorting column 10, the upper and lower ends of said hopper 9 being merged into the riser and sorting columns respectively and constituting an inclined table at the top of the sorting column. A cross bar 11 upon which is centrally mounted a step bearing 12 serves to support the inlet column 6, the cap 7' being provided with a plug 13 which carries a pivot 14. The lower end of the sorting column 10 is provided with a plug 15 which can be removed whenever occasion demands. A service pipe 16 for water discharges into an annular chamber 17 extending around the outer wall of the column 10 and communicating with the interior of said column through orifices 18. Adjacent to the lower end of the column 10 are provided a plurality of discharge outlets 19 through which the larger ingredients of the mixture are discharged. Said outlets are enlarged upwardly and are partly closed by a ring closure 20 which is threaded to the outer wall of the column 10 to adapt it to be adjusted to form the outlets 19 of any desired size. The primary purpose of this closure, however, is to provide simple and efficient means for dislodging any material which

22 clogs the outlets, a condition which occurs frequently in a device of this character. Extending around the upper end of the riser column 7 is an outwardly flared flange 21 which is rigidly secured to the outer wall of the riser 7 and is inclined downwardly toward one side to provide a draining launder for receiving the overflow from the riser 7. A discharge pipe 22 leads from said launder 10 on the lower side. A plurality of radially disposed supporting bars 23 are rigidly connected at their outer ends to the flange 21 and at their inner ends with a collar 24 within which the inlet column 6 is journaled. 15 Standards 25 project upwardly from the bars 23 and support the inlet hopper 2.

The operation of my improved classifier will now be readily understood and briefly stated as is follows: Water being admitted 20 through service pipe 16 into the annular chamber 17 is discharged under a substantially constant head into the sorting column 10 in which the descending mixture is segregated into its constituent parts of different 25 size and weight under the action of gravity. Thus the heavier particles after sinking through the column 10 are discharged through the orifices 19. The lighter portions are conveyed upwardly through the 30 column 10 and hopper 9 into the riser column 7, being eventually discharged into the launder at the top. The feed mixture discharged against the vanes 3, in the manner already referred to imparts rapid rotary 35 movement to the column 6, the reaction due to the discharge through pipes 8 serving to strengthen this action. The material thrown from the pipes 8 on to the wall 9, thoroughly agitates the fluid mixture in the 40 hopper and positively prevents the deposits accumulating on the inclined wall 9 of the hopper. Inasmuch as the material introduced at this point aids very materially in filling the enlarged space within the riser 45 7 the loss of velocity in the ascending current is largely compensated for. As a result, the classification of the ingredients will be continuous and uninterrupted for the reason that the usual zone within which 50 certain portions of the material become suspended is done away with.

What I claim is:

1. A classifier of the character described, comprising a sorting column, a riser column 55 of relatively large diameter surmounting the same, said columns being joined by an

inclined wall, and an inlet column discharging on to said inclined wall, said inlet column being rotatable on its axis.

2. A classifier of the character described, 60 comprising a sorting column of relatively small diameter, a riser column of relatively large diameter surmounting the same, said columns being joined by an inclined wall and a rotatable inlet column provided with 65 outwardly projecting pipes discharging on to said inclined wall.

3. In a classifier of the character described, a sorting column, a hopper at the upper end thereof, a riser column extending 70 above said hopper, an inlet column rotatable about the axis of said riser column, and discharge pipes extending radially from the lower end of said inlet column, said pipes being deflected downwardly and rearwardly 75 toward the inclined walls of said hopper to prevent deposits thereon.

4. In a classifier of the character described, a sorting column provided with a hopper at its upper end, and an inlet column rotatable 80 about the axis of said sorting column and provided with radially extending pipes at the lower end thereof, said pipes being arranged to discharge against the walls of said hopper.

5. In a classifier of the character described, a sorting column, a hopper surmounting the same, and a rotatable inlet column discharging against the walls of said 85 hopper.

6. In a classifier of the character described, a sorting column provided with a hopper at its upper end with upwardly flared walls, an inlet column rotatably mounted above said sorting column, and discharge 90 pipes projecting radially from the lower end of said inlet hopper and discharging against the inclined walls of said hopper.

7. In a classifier of the character described, a sorting column, provided with upwardly enlarged discharge orifices for heavy material, means for supplying water to said column and discharging thereinto above said discharge orifices, and an annulus threaded to the outer wall of said column, said annulus being thus adapted to be raised and lowered relatively to said discharge orifices to vary the sizes thereof.

LEWIS L. BEEKEN.
